COLLAPSIBLE BOX

Alfred James Foord, Aylesbury, England

Application July 26, 1948, Serial No. 40,780
In Great Britain July 31, 1947

2 Claims. (Cl. 217—12)

1

The present invention relates to collapsible boxes of wood or the like firm material.

The boxes will usually be of rectangular prismatic form though the invention can be embodied in other six-sided forms for instance a pyramidal frustum. For convenience the terms top and bottom, sides and ends will be used, but it is to be understood that the invention is not limited to the particular way in which the box stands; also although for reasons which will be explained the largest sides must be the top and bottom, there is no essential relationship between the sizes of the sides and ends.

According to the invention the box comprises a top panel and a bottom panel each battened along all four edges to form a shallow tray, two side panels and two end panels which between them are battened on four edges extending between the top and bottom so that when erected there is one of these battens at each corner of the box, the side and end panels being arranged so that when erected they lie on the inside of the battens on the top and bottom, the parts interlocking so that the side and end panels cannot move normally to nor in their own planes and the whole being held together by metal straps which tie the top and bottom together, while when the box is collapsed the side and end panels can be between the juxtaposed trays aforesaid so that the whole occupies very small volume for transit or storage. The metal straps may be permanent in which case they can be arranged so that their fastenings are accommodated when the box is erected in the recesses formed at the sides by the battens lying outside the side panels, while when the box is collapsed they can be accommodated with the other parts between the two trays.

With the usual rectangular prismatic form of box the top and bottom will be of the same size and can be made identical in form, and when juxtaposed in the collapsed condition of the box, form a very shallow box for the other parts. The two sides will be of the same size and can be made identical in form; the two ends will also be of the same size and can be of identical form. Thus apart from the straps and their fastenings (which may be of quickly operable type and in any case are such as to avoid nails or the like) the box will only comprise three forms of component (two of each) and will readily lend itself to production on interchangeable lines so that if one component is damaged it can readily be replaced. The whole structure is also strong and

2

requires only a minimum of material in proportion to its size and strength.

The invention will be further described with reference to the accompanying drawings which show a preferred embodiment.

Figure 1 is a perspective view of the erected box,

Figure 2 is a perspective view of the bottom of the box with parts of one side and one end prior to erection,

Figure 3 is a cross section on the line III—III of Figure 1,

Figure 4 is a cross section on the line IV—IV of Figure 1,

Figure 5 is a similar section to Figure 3 but with the box collapsed and the loose parts packed inside, and

Figure 6 is a similar view to Figure 4 of a modification.

The box shown in the drawings is of rectangular prismatic form with the sides longer than the ends, but with the height and width approximately the same.

The sides of the box are identical and each 25 consists of a plain rectangular panel 1. The ends of the box are identical and each consists of a plain panel 2 and two battens 3 secured along its vertical edges.

The top and bottom of the box are also identical and each comprises a panel 4, a plain batten 5 across the whole length of each end edge, and another batten 6 along each side edge. These battens stop short of the end battens 5 by a distance equal to the thickness of the end panels 1 and are notched at 7 over a length equal to the thickness of the battens 3. When the ends and top and bottom are assembled, the top and bottom edges of the panels 2 rest on the faces of the panels 4 and fill the spaces between the ends of the battens 6 and the battens 5, while the ends of the battens 3 which terminate short of the top and bottom edges of the panels 2 just fit into the notches 7. This prevents any inward or outward movement of the ends in relation to the top and bottom.

When the side panels 1 are assembled their end edges lie against the panels 2 and their top and bottom edges against the panels 4, while their outer faces bear against the battens 6. Thus the panels 1 cannot move outwards nor in their own planes. They are prevented from moving inwards by engagement with shoulders 8 spaced inwards from the inside of the battens 6 by the thickness of the panels 1. As the panels 1 cannot move inwards and the battens 3 bear against

their outer faces, the end panels 2 cannot move in their own planes.

In the construction shown the shoulders 8 are formed by grooves 9 in bevelled beads 10 integral with the battens 6 these beads being of less height than the battens. This construction makes the height of the side panels 1 somewhat less than the internal height of the box and so enables them to be accommodated within the trays which the top and bottom form although the box shown is nominally of the same height as its width.

Figure 1 also shows the battens 5 and 6 tied together by metal strappings 11 which may conveniently extend over the whole length of the battens 6. These strappings form an additional means of preventing movement of the end panels 2 in their own planes. To avoid obscuring the notches 7, the strappings 11 are not shown in Figure 2.

The box shown is held together by metal straps 12 secured to the top and bottom and terminating in rapid fastenings such as the toggle fastenings 13. There are two such straps 12 lying about a quarter of the length of the box in from the ends, on each of the two sides. The straps lie against the outer faces of the side panels 1 and their thickness being accommodated in grooves 14 in the battens 6. The fastenings 13 are wholly accommodated within the recesses formed by the battens 3 and 6. To enable the straps to be detached when the box is collapsed, they are held in place by lugs 15 formed by bending them at right angles, these lugs being housed in notches 16 in the battens 6. The grooves 14 are cut right through the beads 10 to enable the lugs to be withdrawn from the notches 16.

When the box is collapsed, by juxtaposing the tray-like top and bottom a shallow box is formed, in which as the top and bottom are the members of largest area, the sides, ends and straps can be accommodated, as indicated in Figure 5.

Instead of using the straps 12 the box may, as shown in Figure 6, be held together by tensioned metal straps 17 wrapped right round the box at the same locations as the above mentioned straps 12, and secured by any means which secures the straps without the use of fastenings which penetrate the wood, it being essential to the invention to avoid the use of nails or screws which have to be driven in to close the box and withdrawn to open and collapse it. Strap securing means of this kind are well known per se. With such straps, it is advantageous to insert short battens 18 at their location, extending across the side panel 2 between the battens on the top and bottom.

Where toggle fastenings such as 13 are used, the maximum strength is obtained by the use of

hardwood for all battens, but where tensioned strapping such as 17 is used, softwood battens should be satisfactory. The wall panels may advantageously be of plywood.

5 I claim:

1. A collapsible box comprising a pair of identical, rectangular, plain, plywood side panels, a pair of identical rectangular, plywood end panels, an end batten on each vertical edge of said end panels stopping short of the top and bottom edges of the panels, a rectangular, plywood top panel, and a rectangular plywood bottom panel identical to said top panel plain battens secured along the full length of both end edges of said top and bottom panels, side battens secured to each side edge of said top and bottom panels and stopping short of the end edge panels by the thickness of said end panels, said side battens being each divided by a longitudinal groove into 10 an outer side batten portion next to the panel edge and a shoulder strip on its inside, said longitudinal groove being adapted to receive said side panels, the ends of said outer side batten portions being notched to receive the ends of said end battens which abut inwardly against the shoulder strips and prevent endwise movement of the end panels, and metal straps having rapid fastenings secured to said top and bottom panels, which when the box is erected tie the top and bottom panels together, the fastenings being accommodated on the outside of the side panels but within the recess formed between the side and end battens.

2. A box as specified in claim 1 wherein at two points equidistant from the ends of each side batten the shoulder strip is cut away and the inside and underside of the outer side batten portion are recessed for detachable engagement with right angle lugs formed at the ends of said metal straps.

40 ALFRED JAMES FOORD.
